UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

AUTOMATIC SEWING-MACHINE.

1,342,367.

Specification of Letters Patent. Patented June 1, 1920.

Application filed September 14, 1917, Serial No. 191,328. Renewed October 2, 1919. Serial No. 328,083.

To all whom it may concern:

Be it known that I, ERASTUS E. WINKLEY, a citizen of the United States, residing at Lynn, in the county of Essex and State of Massachusetts, have invented certain new and useful Improvements in Automatic Sewing-Machines; and I do hereby declare the following to be a full, clear, and exact description of the invention, such as will enable others skilled in the art to which it appertains to make and use the same.

The invention relates to automatic machines in which the requisite relative movements between the work and means for operating thereon are automatically controlled and effected to maintain the work and operating means in proper relation as the point of operation progresses along the work.

20 In welt and turn sewing machines, outsole stitchers, rounding and channeling machines, and various other shoe machines, it is necessary during the feed of the shoe to change the angular relation of the operating means and work by relatively tipping said means and the shoe both transversely and longitudinally of the line of feed to maintain the operating means and shoe in proper relation at the point of operation.

25 30 In an application filed May 25, 1916, Serial No. 99,751, a machine is shown and described in which the relative transverse and longitudinal tipping movements are controlled by feelers acting adjacent to the path of travel at the point of operation along the work. In this machine the transverse tip is determined throughout the operation along the work by the contour of the work engaged by the controlling feeler.

35 40 45 50 In doing certain classes of work, it is desirable or important that an additional relative tip between the operating means and the work not indicated by a change in the contour of the work, be secured at certain points in the travel of the point of operation. For instance, in sewing the inseam of a welt or turn shoe the shoe or sewing mechanism should be tipped transversely when sewing about the toe (and in some cases when sewing through the shank) to a greater degree than is indicated by the change in the contour of the sole adjacent

to the channel. It is accordingly the primary object of the present invention to provide means for securing the above result. 55 To this end the invention contemplates the provision in a machine in which a feeler acting along a contour of the work acts to vary the angular relation between the work and operating means in accordance with 60 said contour of means for effecting a change in said angular relation not indicated by the feeler. In embodying the invention in an inseam sewing machine such as shown in the above application, to secure an additional or abnormal lateral tip when operating about the toe or when operating about the toe and through the shank, it is preferred to effect the required change in the angular relation of the sewing mechanism 70 and shoe by a cam moving with the shoe and acting to so vary the connections between the feeler and the mechanism which relatively tips the sewing mechanism and shoe, that this mechanism effects an additional tip without a corresponding change 75 in the position of the feeler.

In addition to the features of invention indicated above, the invention also includes certain further features of construction and 80 combinations of parts which will be hereinafter described and set forth in the claims. The various features of the invention will be readily understood from an inspection of the accompanying drawings and the following detailed description of the mechanism 85 illustrated therein.

In the drawings, Figure 1 is a side elevation showing so much of the automatic inseam sewing machine of the application 90 above referred to as is necessary to illustrate the application of the present invention thereto; Fig. 2 is a detail end view of the mechanism for varying the connections between the controlling feeler and the mechanism 95 for determining the angular position of the sewing head; and Fig. 3 is a detail plan view of the parts shown in Fig. 2.

In the machine shown in the drawings, the means for operating on the shoe consists 100 of a sewing mechanism indicated at 2, which is similar in construction to the well-known Goodyear welt and turn sewing machine shown and described in Patent No. 412,704,

October 8, 1889. The shoe to be operated on is carried on a freely movable and rotatable jack 4 which is automatically swung during the sewing to vary the angular relation of the work and sewing mechanism and thus maintain the bottom of the channel or base of the insole lip in the line of feed by correcting mechanism such as shown in Patent No. 1,088,390, which is controlled by a 5 feeler 6 acting along the channel approximately at the sewing point, as fully shown and described in the application above referred to. The sewing mechanism is mounted on a support or head 8, which is automatically tipped both transversely and longitudinally of the feed during the sewing to 10 vary the angular relation of the work and sewing mechanism, and thus maintain the sewing mechanism in proper relation to the 15 surface of the sole at the sewing point by correcting mechanisms which are controlled by feelers acting along the surface of the sole adjacent to the channel and approximately at the sewing point. For the sake of 20 simplicity, the same feeler 6 which controls the swinging movements of the jack is also utilized to control the longitudinal tipping movements of the support 8 for the sewing mechanism, the horizontal position of the 25 end of the feeler determining the swinging movement of the jack and the vertical position of the end of the feeler determining the tipping movements of the head. The 30 transverse tipping of the head 8 is determined and controlled by the vertical position of a second feeler 10 which engages the 35 surface of the shoe sole within the channel. The vertical position of the end of the feeler acts through mechanism, more fully shown 40 and described in the above application and indicated generally at 12, to control a mechanism which determines the position of the head 8 on the segmental guideways 14, and consequently the lateral tip of the sewing 45 mechanism with relation to the shoe sole.

The mechanism for moving and determining the position of the head 8 on the segmental guideways comprises a reciprocating roll carriage 16 connected by a link 18 to a lever 50 20, which in turn is connected by a link 22 with the lower end of the lever 24, the upper end of which bears against a sleeve 26 mounted to slide on the rotary carrier 28 on which the ways 14 are formed. The sleeve 55 is connected with the head 8 through a bar 30, bell crank lever 32, and links 34 and 36, as more fully described in Patent No. 1,082,185. The roll carriage is mounted to reciprocate on guide bars 38, and is provided with two pivoted roll carriers 40 in which are mounted rolls engaging a continuously rotating drum 42. The outer ends 60 of the roll carriers are provided with arms, the ends of which are connected by a link 44 65 which is connected by a link 46 to the end of

the lever 48, as more fully shown and described in the application above referred to. The other end of the lever 48 carries a roll 70 engaging an annular groove 50 in the hub of a controller cam 52 mounted to rotate and slide longitudinally on a shaft 54 which makes one revolution for each cycle of the sewing mechanism. The position of the controller cam lengthwise of its shaft determines the position of the roller carriage 16 75 lengthwise of the drum 42, and the position of the carriage in turn determines the lateral tip of the sewing mechanism. A change in the position of the controller cam will swing the lever 48, and thus turn the 80 roll carriers 40 so that the rolls carried thereby will stand at an angle to the drum 42. When this occurs, the roll carriage will travel lengthwise of the drum until this travel restores the rolls to position with 85 their axes parallel to the axis of the drum, after which the rolls will rotate idly until they are again turned at an angle by another shift in the position of the controller cam. The movement of the roll carriage 90 will, through the connections described, cause a change in the lateral tip of the sewing mechanism. The position of the controller cam, and consequently the lateral tip 95 of the sewing mechanism, is determined by a controller roll 56, which has a diameter substantially equal to the width of the central groove 58 of the controller cam, and is so mounted that it may be moved into the path of one or the other of the inclined cam 100 surfaces 60 which lead to the central groove. If the controller roll is in line with the central groove of the controller cam at the time in the cycle of operations that the roll enters the groove, the roll will pass idly through 105 the groove and the position of the roll carriage, and consequently the lateral tip of the sewing mechanism, will remain unchanged. If the controller roll is at one side or the other of this position at the time 110 in the cycle of operations when it enters the groove in the controller cam, one of the cam surfaces 60 will ride against the roll, shifting the controller cam on its shaft and thus 115 effecting a change in the lateral tip of the sewing mechanism. The position of the controller roll 56 during each cycle of operations is controlled by the vertical position of the feeler 10 through the mechanism indicated at 12, which is connected with the 120 roll through wires 62 and 64 having their ends connected with the bar 66 which carries the roll, and with a disk 68, the position of which is determined during each cycle of 125 the sewing mechanism by the vertical position of the end of the feeler 10 when in engagement with the surface of the shoe sole.

As thus far described, the machine corresponds in construction and mode of operation to the machine shown and described in 130

the application above referred to. In addition to the mechanism for controlling the lateral tip of the sewing mechanism by the feeler engaging the shoe sole, the machine 5 shown is also provided with means for securing at any desired point, or during any desired portion of the sewing operation, additional or abnormal lateral tip not indicated by the feeler. As shown, this means 10 comprises one or more cams moving in unison with the shoe and connected to shift the controller roll 56 with relation to the mechanism through which the feeler acts upon it. The lateral tip of the sewing mechanism corresponding to any given vertical position of the end of the feeler may thus be changed while operating along any predetermined part of the shoe, without interfering with the action of the feeler in 15 effecting changes in the lateral tip indicated by changes in the contour of the sole along such portion of the shoe. To enable the position of the controller roll to be changed without a corresponding change in the 20 feeler or feeler mechanism, the end wires 25 62 and 64 are connected with the bar 66 by means of a rod 70 which passes through the bar and is so connected therewith that the bar may be moved endwise with relation thereto. As shown, the rod is provided 30 near one end with a screw thread 72 engaged by internal threads on a pinion 74 which is held from endwise movement within a slot 76 in the bar. The rod is held 35 from rotation in the bar by a pin 78 passing through a slot 80 in the rod. By turning the pinion 74 the bar and controller roll 56 carried thereby may be shifted endwise to vary the lateral tip of the sewing mechanism 40 without changing the position of the rod 70. Any endwise movement of the rod 70, however, results in a corresponding movement of the bar and controller roll. The pinion 74 is engaged by a gear segment 45 82 secured to the end of a rock sleeve 84. The rock sleeve carries a bell crank lever 86, one arm of which is connected with a spring 88 tending to move the gear segment in one direction, and the other arm of 50 which rests upon one arm of a bell crank lever 90. The other arm of the bell crank lever 90 is connected by a link 92 to the arm of a second bell crank lever 94, the other arm of which is connected by a link 96 55 with the rear end of the lever 98. The forward end of the lever 98 engages the upper surface of a cam plate 100 which is secured to the rotary head 102 through which the jack is rotated. The cam plate is provided 60 with a cam 104 which acts through the connections described to turn the pinion 74 to increase the lateral tip of the sewing mechanism when sewing about the toe of the shoe. The cam plate may also be provided with 65 cams 106 for turning the pinion 74 to in-

crease the lateral tip of the sewing mechanism in sewing through the shank, should such additional tip be desirable.

While the invention has been shown and described as embodied in a mechanism for 70 varying the relative lateral tip between a shoe and a sewing mechanism, it will be understood that it is not confined in its application to such a mechanism or machine, but may, if found desirable, be embodied in 75 mechanisms for otherwise varying the angular relation of the shoe and sewing or other operating mechanism.

It will also be understood that the specific construction and arrangement of parts 80 shown and described is not essential to the broader features of the invention, and may be varied or modified as found desirable or best suited to the construction and arrangement of the mechanism or machine in 85 which it is to be embodied.

Having explained the nature and object 90 of the invention and specifically described one form of mechanism in which it may be embodied, what is claimed is:

1. An automatic machine, having, in combination, operating means and a work support relatively movable to transfer the point of operation along the work, mechanism for varying the angular relation of the operating means and work, a feeler acting along a 95 contour of the work for controlling said mechanism to regulate the angular relation in accordance with the contour, and additional means for effecting a change in said 100 angular relation not indicated by the feeler.

2. An automatic machine, having, in combination, operating means and a work support relatively movable to transfer the point of operation along the work, mechanism for 105 determining the angular relation of the operating means and the work, a feeler acting along the contour of the work for controlling said mechanism, and means for varying the relation between the feeler and said mechanism when acting along different parts of 110 the work.

3. An automatic machine, having, in combination, operating means and a work support relatively movable to transfer the point 115 of operation along the work, mechanism for varying the angular relation of the operating means and work, including a controller, the position of which determines the angular relation, means for varying the position of the 120 controller in accordance with the contour of the work, and means for independently varying the position of the controller.

4. An automatic machine, having, in combination, operating means and a work support relatively movable to transfer the point 125 of operation along the work, mechanism for varying the angular relation of the operating means and work, including a controller, the position of which determines the angular 130

relation, a feeler acting along the contour of the work for varying the position of the controller in accordance with said contour, and means for independently varying the position of the controller.

5. An automatic machine, having, in combination, operating means and a work support relatively movable to transfer the point of operation along the work, mechanism for 10 varying the angular relation of the operating means and the work, including a controller, the position of which determines the angular relation, a feeler acting along the contour of the work for varying the position of the controller in accordance with said contour, and a cam moving in time with the work for 15 independently varying the position of the controller.

6. An automatic machine, having, in combination, operating means and a work support relatively movable to transfer the point of operation along the work, mechanism for 20 relatively tipping the operating means and work transversely, a feeler acting along the work for controlling said mechanism, and means for effecting a relative transverse tip 25 not indicated by the feeler.

7. An automatic machine, having, in combination, operating means and a work support 30 relatively movable to transfer the point of operation along the work, a feeler acting along the work, mechanism controlled by the feeler for relatively tipping the operating means and work, and means for independently controlling said mechanism.

8. An automatic machine, having, in combination, operating means and a work support 35 relatively movable to transfer the point of operation along the work, a feeler acting along the work, mechanism controlled by the feeler for relatively tipping the operating means and work transversely, and means for giving an additional tip not indicated by the feeler along a predetermined part of the 40 work.

9. An automatic shoe sewing machine, having, in combination, sewing mechanism, a

shoe supporting jack, mechanism for relatively tipping the sewing mechanism and jack transversely in accordance with the 50 transverse curvature of the shoe sole adjacent to the seam, and mechanism for giving an additional tip while sewing along predetermined portions of the shoe.

10. An automatic shoe sewing machine, 55 having, in combination, sewing mechanism, a shoe supporting jack, mechanism for relatively tipping the sewing mechanism and jack transversely in accordance with the transverse curvature of the shoe sole adjacent to the seam, and mechanism for giving an additional tip while sewing about the 60 toe.

11. An automatic shoe sewing machine, having, in combination, sewing mechanism, a 65 shoe supporting jack, mechanism for relatively tipping the sewing mechanism and the shoe, a feeler engaging the shoe sole adjacent the sewing point for controlling the tipping mechanism during the sewing, and means 70 for giving an additional relative tip while sewing along certain portions of the shoe.

12. An automatic shoe sewing machine, having, in combination, sewing mechanism, a shoe supporting jack, mechanism for relatively tipping the sewing mechanism and the shoe transversely, a feeler engaging the shoe sole adjacent the sewing for controlling the tipping mechanism during the sewing, and means for giving an additional transverse 80 tip while sewing along certain portions of the shoe.

13. An automatic shoe sewing machine, having, in combination, sewing mechanism, a shoe supporting jack, mechanism for relatively tipping the sewing mechanism and shoe, a feeler engaging the shoe sole adjacent the sewing point for controlling the tipping mechanism during the sewing, and a cam moving in time with the shoe for independently controlling the tipping mechanism 85 during the sewing.

ERASTUS E. WINKLEY.
